(57) **CLAIM**

The ornamental design for a display panel or screen with an animated graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first image of a first embodiment of a display panel or screen with an animated graphical user interface showing my new design;

FIG. 2 is a second image thereof; and

FIG. 3 is a third image thereof;

FIG. 4 is a front view of a first image of a second embodiment thereof;

FIG. 5 is a second image thereof; and,

FIG. 6 is a third image thereof.

The outermost even-dash broken lines showing a display panel or screen form no part of the claimed design. The remaining broken lines shown in FIGS. 3 and 6 are part of the claimed design.

The appearance of the image transitions sequentially between the images shown in FIGS. 1-3 and FIGS. 4-6.

The subject matter in this patent includes a process or period in which an image changes into another image. This process or period forms no part of the claimed design.
